UNITED STATES PATENT OFFICE.

HENRY J. GAISMAN, OF NEW YORK, N. Y.

TOBACCO PIPE.

Application filed June 21, 1923. Serial No. 646,767.

To all whom it may concern:

Be it known that I, HENRY J. GAISMAN, a citizen of the United States, and resident of New York city, in the county of New York and State of New York, have invented certain new and useful Improvements in Tobacco Pipes, of which the following is a specification.

The object of my invention is to provide a tobacco pipe having simple and efficient means to enable the smoke passageway to be readily blown out, or cleaned by passing any suitable cleaner through it, without requiring the stem to be removed from the bowl, and to maintain tight joints while the pipe is being smoked.

In carrying out my invention I provide a body having a bowl for the tobacco and a duct communicating with the bowl, a stem having a bore and provided with an extension rotative in said duct, said extension having a longitudinal passage or channel communicating with the bore in the stem, said body having an outlet bore communicating with said duct, said extension being adapted to close said bore when the stem and extension are in the smoking position, said stem and extension being rotative to present said channel or passage in communication with said outlet bore when the stem is to be cleaned, whereby the user may blow through the stem and extension to expel nicotine and other accumulation from the stem and extension, or may pass a cleaner through the same, at which time the extension will close the communication between the bowl and said duct.

Reference is to be had to the accompanying drawings forming a part hereof, wherein

Fig. 1 is a plan view of a tobacco pipe embodying my invention;

Fig. 2 is a section on line 2, 2, in Fig. 1 showing the parts in position for use;

Fig. 3 is a cross section on line 3, 3, in Fig. 2;

Fig. 4 is a view similar to Fig. 2, showing parts in position for cleaning; and

Fig. 5 is a section on line 5, 5, in Fig. 4. Similar numerals of reference indicate corresponding parts in the several views.

The numeral 1 indicates the body of the pipe which may be provided with any suitable tobacco bowl or recess 2, said body having a duct at 3 in communication with the bowl at 4, and at 5 is the stem of the pipe.

Said parts may be of any usual and desired material and construction, the stem being shown provided with a reduced portion 5^a rotative in duct 3 in any ordinary way. The stem 5 is provided with an extension 6 axially disposed respecting said stem and snugly fitted to rotate within the duct 3, the inner end of said extension being shown located at the point of communication 4 between the bowl and the duct. The extension 6 may be of any suitable material and secured to stem 5 by any desired means, or may be integral with said stem. The bowl is provided with an outlet or discharge bore 7 communicating and in register with duct 3 below the bowl. The stem 6 has a longitudinal channel or passage 6^a which communicates with the bore 5^b in stem 5 and is adapted to communicate at its inner end 75 with the bowl at the point 4 and also with the bore 7 according to the position of the stem in respect to the bowl. For convenience of manufacture and use the channel or passage 6^a is shown formed in one side of 80 extension 6 so that said channel is at one side of the longitudinal axis of extension 6, and the bore 7 is on the opposite side of said axis. The bore 5^a of stem 5 registers with the channel 6^a that is disposed eccentrically 85 respecting extension 6. When the parts are in the position shown in Fig. 2 the channel 6^a will communicate with the bowl for smoking and the adjacent end of extension 6 will close the bore 7, and when the parts are in 90 the position shown in Fig. 4 the extension 6 will obstruct communication between the bowl and duct 3 and the channel or passageway 6 will be in communication with the bore 7 for cleaning. The inner end of extension 6 and the adjacent end wall 3^a of the duct 3 at the inner end of bore 7 are shown located transversely respecting the axis of the stem and abut, having smooth cooperating surfaces serving in the nature of a valve 100 to obstruct or close bore 7 when the parts are in position for smoking to prevent leakage of nicotine, moisture and the like through said bore and to obstruct the entrance of air through the bore during smoking. In other words, the channel 6^a communicates with the bowl and extension 6 closes duct 7 simultaneously.

When the parts are in the position shown in Fig. 2 the pipe may be smoked in an ordinary way, the smoke traveling from the bowl through channel or passage 6^a and

through bore 5^b. When the user desires to clean the pipe he will rotate the stem and its extension 6 until the channel 6^a registers with bore 7, whereupon, since the channel will be out of register with the bowl, he may blow through the stem and the extension to blow any nicotine, moisture, accumulated tobacco, etc., through the outlet bore 7, or he may run a cleaner through 10 the bore 5^b, channel 6^a and bore 7 and then restore the stem and extension to position for use. By means of my improvements a tobacco pipe may be readily kept clean in its passages without requiring the stem to 15 be removed and without soiling the fingers, which frequently occurs where the stems of pipes are removed in order to clean the stem and the duct communicating with the bowl.

20 Having now described my invention what I claim is:—

1. A tobacco pipe comprising a body having a bowl and a duct communicating therewith, a stem rotatively fitted to the body 25 and provided with a bore and an extension having a channel communicating with said bowl and adapted to register with the bowl, said body having an outlet bore communicating with said duct adapted to communicate with said channel when the stem is 30 out of smoking position.

2. A tobacco pipe comprising a body having a bowl and a duct communicating therewith, a stem rotatively fitted to the body 35 and provided with a bore and an extension having a channel communicating with said bowl and adapted to register with the bowl, said body having an outlet bore communica-

cating with said duct adapted to communicate with said channel when the stem is 40 out of smoking position, said extension having an inner portion in position to obstruct communication between the duct and the bore when the stem is in one position and having a portion to obstruct communication 45 between the bowl and the duct when the stem is in another position.

3. A tobacco pipe comprising a body having a bowl and a duct communicating therewith, a stem rotatively fitted to the body 50 and provided with a bore and an extension having a channel communicating with said bore and adapted to register with the bowl, said body having an outlet bore communicating with said duct adapted to communicate with said channel when the stem is out of smoking position, said duct having a smooth inner wall adjacent to the inner end of the bore, said stem having a smooth inner end cooperative with said wall 60 to obstruct the passage through the bore when the stem is in smoking position.

4. A tobacco pipe comprising a body having a bowl and a duct communicating therewith, a stem rotatively fitted to the body 65 and provided with a bore and an extension having a channel located eccentrically along a side of the stem, said channel communicating with said bore, said channel adapted to communicate with the bowl, the body having an outlet bore communicating with said duct, said extension closing said bore and said channel communicating with the bowl simultaneously.

HENRY J. GAISMAN.
